UNITED STATES PATENT OFFICE.

HENRY VINCENT JAMES, OF RADLETT, ENGLAND.

MATERIAL-FEED-REEL BRAKE.

1,383,953.

Specification of Letters Patent.

Patented July 5, 1921.

Application filed March 23, 1918. Serial No. 224,362.

To all whom it may concern:

Be it known that I, HENRY VINCENT JAMES, a citizen of the United Kingdom of Great Britain and Ireland, and resident of 5 "Cintra," Aldenham avenue, Radlett, in the county of Hertfordshire, England, have invented certain new and useful Improvements in Material-Feed-Reel Brakes, of which the following is a specification, such as will enable others skilled in the art to which it 10 pertains to make and use the same.

This invention relates to material feed reel brakes and more particularly to electrically operated brakes for material feed reels 15 used in connection with rewinders, textile, paper making and printing machinery and while applicable for these several purposes it is especially designed for use with paper feed reels of rotary web fed printing presses, 20 to which application my description of the invention will particularly refer. The object of my invention may be described as a means whereby the effective brake applied to a feed reel brake member at constant radius 25 will be automatically varied as the diameter of the reel and the varying leverage applied to the brake through the reel as it is unwound—and particularly the accomplishment of this object by electrical means, and 30 without the employment of any apparatus bearing upon the winding face of the feed reel or the material both of which methods allow of detrimental effects upon the material.

As an example, and referring to rotary web fed printing presses I will explain that it is almost invariably necessary to feed paper to the printing cylinders under a constant web tension and that the necessary tension varies widely in different actual printing units which may be employed in multiple as one printing press. This tension is usually obtained by means of a brake on the feed reel but in earlier patents granted to 40 me I show a means of obtaining constant web feed tension other than by brake upon the feed reel, which I therein employ only for the purpose of preventing reel overrun and this present further application has 45 reference also to such brakes, where the degree of brake to prevent overrun must be proportionate to the diameter of the reel so as to be capable of overcoming its maximum momentum at maximum diameter and 50 speed as the press is quickly slowed down

or stopped, and on the other hand where such brake only must be applied as is necessary to overcome the momentum of the reel or minimum diameter to prevent fracture of the web by excessive brake.

My invention consists in the employment of means whereby an electricity controller capable of regulating the effective supply of electrical energy to the electrically operated brake has motion applied to it by the weight 60 of the feed reel through a given travel in a downward direction said weight acting against springs or other counter balance tending to apply motion in the reverse direction against the maximum weight of the reel, 65 such springs or counter balance being capable of imparting motion to the regulator in the reverse direction by overcoming the weight of the reel and imparting motion to the latter in an upward direction as it is 70 unwound and its weight reduced, the various parts being so proportioned that the maximum weight of the reel will cause the necessary maximum travel of the controller 75 in one direction and the springs or counter balance will cause the necessary maximum motion of the controller in the reverse direction with minimum reel diameter and weight. In my co-pending application, Ser. No. 191,979, filed Sept. 18, 1917, is disclosed 80 the form of electro-magnetic brake illustrated in this application.

One method of carrying my invention into effect is shown in the accompanying drawings in which Figure 1 shows part of the 90 side frame and reel bracket of a printing press. Fig. 2 shows the other side of the frame showing the electrically operated brake. Fig. 3 is a front elevation showing certain parts in section and showing the 95 electrical connections between the rheostat, the electro-magnetic brake and the source of current.

a is the reel bracket of a printing press which supports a feed reel *b*, by means of a usual spindle *c* which is mounted in bearings *d* one only of which is shown. This bearing is movably supported in the bracket *a* and rests upon the top of springs *e*. The springs are let into recesses *f* in the bracket *a*.

On the bracket *a* I mount a slate or other insulating slab *g* by means of bars *h* and on this slab I fit a radial two way switch *i* the brushes *j* of which are mounted upon a pivoted lever *k* so as to be equally and 110

simultaneously moved when the lever turns upon its pivot. The brushes j are insulated from the lever at x . Rigidly connected to the lever k is short crank l connected to the bearing d by a link m .

Referring to Fig. 2, it will be seen that a brake drum n is keyed or otherwise suitably secured to the spindle c . The braking surface p is disposed between the magnetic pole pieces r and r' . These pole pieces are supported in a cradle s pivoted at o to the side frame. The magnet coil t is disposed between the pole pieces. A spring keeps the braking surface p constantly in contact with the drum n . The pole pieces r and r' are machined so as to have a greater radius from the center c than the surface p . Consequently, these pole pieces are always closely adjacent but never in contact with the surface n . When the magnet is energized, drum n partially closes the magnetic field of the electromagnet and braking action is established, which action will vary with the electrical energy fed to the magnet. This form of electro-magnetic friction brake is disclosed and claimed in my co-pending application, Ser. No. 191,979, filed Sept. 18, 1917, which became Patent No. 1,327,046, Jan. 6, 1920.

As shown in Fig. 3 a source of current is connected by wires 11 and 12 to binding posts 13 and 14 respectively, on the rheostat. The rheostat has another pair of binding posts 15 and 16 connected to wires 17 and 18 respectively, which in turn are connected to a pair of binding posts 19 and 20 on the brake and connected to the coil t thereof. The current from the source passes through wires 11 and 12 to the rheostat where it is varied in accordance with the position thereof and from there passes through wires 17 and 18 to the coil t to energize the same in accordance with said varied current.

It will be seen in the drawing that the springs e are supporting the full weight of the reel b and it will be evident that as the reel is run off and its weight decreases the springs will lift the bearing d and with it the link m thus turning the lever k and moving the brushes j over their contacts thereby regulating the current supplied to the brake in correct proportion to the reduced diameter and weight of the reel.

What I claim and desire to secure by Letters Patent is:—

1. In combination with a spindle for a material feed reel; of a brake acting on said spindle to retard rotation thereof; means in which said spindle is mounted for rising and falling movements; means for counter-balancing the weight of the spindle and the material thereon, said means causing the spindle to rise as the weight thereon reduces; and means connected to said brake for op-

erating the same and controlled by the rising movements of the spindle for causing the effective braking action of the brake on the spindle to vary as the material is fed from the spindle.

2. In combination with a spindle for a material feed reel; of a brake acting on said spindle and comprising a brake drum mounted on the spindle, said brake being provided to retard the rotation of the spindle; vertically movable bearings in which the spindle is mounted and whereby the spindle is capable of rising and falling movements; springs for counterbalancing the weight of the spindle and the material thereon, said springs causing the bearings and spindle to rise as the weight on the spindle decreases; means connected to the bearings and controlling the effective operation of the brake whereby the braking action of the brake on the brake drum is varied as the material is fed from the spindle.

3. In combination with a spindle for a material feed reel; of a brake drum mounted on the spindle; vertically movable bearings in which the spindle is mounted and whereby the spindle is capable of rising and falling movements; springs for counterbalancing the weight of the spindle and the material thereon, said springs causing the spindle to rise as the weight of the material on the spindle decreases; and an electric brake co-operating with the brake drum on the spindle and capable of retarding the rotation of the spindle; a rheostat electrically connected to said brake; and connections between the rheostat and the vertically movable bearings for operating the rheostat to vary the effective braking operation of the electric brake as the weight of the material on the spindle decreases.

4. In combination with a spindle for a material feed reel; of an electro-magnetic brake for retarding the rotation of the spindle shaft; means in which the spindle is mounted for rising and falling movements; and means connected to the means in which the spindle is mounted and controlled by the rising movements of the electro-magnetic brake on the spindle as the weight of the material on the spindle decreases.

5. In combination with a spindle for a material feed reel; means in which said spindle is mounted for rising and falling movements; means for counter-balancing the weight of the spindle and the material thereon, said means causing the spindle to rise as the weight thereon reduces; and a brake for acting on said spindle to retard the rotation of the same, said brake being mounted for rising and falling movements to follow the movements of the spindle.

6. In combination with a spindle for a material feed reel; means in which said

- spindle is mounted for rising and falling movements; means for counter-balancing the weight of the spindle and the material thereon, said means causing the spindle to rise as the weight of the material thereon is reduced; a brake for acting on said spindle to retard the rotation of the same, said brake being mounted for rising and falling movements to follow the movements of the spindle; and means operated by the means in which the spindle is mounted for controlling the effective brake action of the brake as the spindle rises.
7. In combination with a spindle for a material feed reel; means in which said spindle is mounted for rising and falling movements; means for counter-balancing the weight of the spindle and the material thereon, said means causing the spindle to rise as the weight of the material thereon is reduced; and an electro-magnetic brake for acting on said spindle to retard the rotation thereof, said electro-magnetic brake being mounted for rising and falling movements
- 5 movements to follow the rising and falling movements of the spindle.
8. In combination with a spindle for a material feed reel; means in which said spindle is mounted for rising and falling movements; means for counter-balancing the weight of the spindle and the material thereon, said means causing the spindle to rise as the weight of the material thereon is reduced; an electro-magnetic brake for acting on said spindle to retard the rotation thereof, said electro-magnetic brake being mounted for rising and falling movements to follow the rising and falling movements of the spindle; and electric current controlling means controlled by the rising movements of the spindle for varying the effective braking action of the brake.
- 10 15 20 25 30 35 40

In witness whereof I have hereunto set my hand in presence of two witnesses.

HENRY VINCENT JAMES.
